UNITED STATES PATENT OFFICE

126,862

DESIGN FOR A VACUUM BEAUTY BONNET

Dolletta M. Ackerman, Los Angeles, Calif.

Application March 2, 1940, Serial No. 90,634

Term of patent 7 years

To all whom it may concern:

Be it known that I, Dolletta M. Ackerman, a citizen of the United States, residing at Los Angeles, in the county of Los Angeles and State of California, have invented a new, original, and ornamental Design for a Vacuum Beauty Bonnet, of which the following is a specification, reference being had to the accompanying drawing, forming part thereof.

Fig. 1 is a perspective view of a vacuum beauty bonnet embodying my new design;

Fig. 2 is a side elevational view of the same; and

Fig. 3 is a front elevational view of the same.
I claim:

The ornamental design for a vacuum beauty bonnet, as shown.

DOLLETTA M. ACKERMAN.
